UNITED STATES PATENT OFFICE

PERCY B. CAMP, OF MAYWOOD, ILLINOIS, ASSIGNOR TO UNIVERSAL DRAFT GEAR ATTACHMENT CO., A CORPORATION OF ILLINOIS

CLEVIS FOR BRAKES

Application filed December 4, 1926, Serial No. 152,587. Renewed March 5, 1931.

This invention relates to brake mechanism and has for its principal object to provide a clevis that can be attached to the small links of standard brake chains, that will not interfere with or foul with other parts in movement, and that can be produced economically. Further objects and various advantages of the invention will become apparent as the disclosure proceeds and the description is read in connection with the accompanying drawings, in which

Fig. 1 is a diagrammatic view illustrating uses of the improved clevis in connection with a well known hand brake;

Fig. 2 is an enlarged side elevation of the clevis in a form suitable for connecting a brake chain to a push rod;

Fig. 3 is a longitudinal section taken on the line 3—3 of Fig. 2;

Fig. 4 is a longitudinal section taken on the line 4—4 of Fig. 3, and

Fig. 5 is a side elevation of a modified form applicable to a different type of push rod.

Referring to the diagram in Fig. 1, 10 indicates a conventional brake shaft to which is secured the live end of a brake chain 11, the dead end of which is anchored to the brake shaft step 12, and the bight of which cooperates with a sheave 13 journaled in a jaw 14, carried by hand brake rod 15, the opposite end of which is connected with the push rod 16 of a brake cylinder 17 by another chain 18. The push rod 16 is also connected with a cylinder lever 19 of the foundation brake gear.

In such an organization the improved clevis, generally indicated by 20, is useful in three places; first, in connecting the chain 18 with the push rod or foundation brake gear; second, in connecting the chain 18 with the hand brake rod 15 and, third, in connecting the dead end of the chain 11 with the brake shaft step 12.

The clevises now in common use include a U-shaped portion provided with large eyes which receive a cross-pin. The eyes are too large to pass through the small links of standard chain used in brake mechanisms and, in consequence, it has been necessary to equip such chains with extra and specially made links.

In Figs. 2, 3 and 4, the clevis includes a plate 21 perforated adjacent each end, as indicated at 22 and 23, an opposed plate 24 carrying a pin 25 passing through the push rod 16 and the perforation 22, and a pin 26 passing through a link in the chain 18 and the perforation 23.

The plate 24 is beveled adjacent its ends, as indicated at 27 and is reenforced between its ends by a tapering rib 28, the outer edge of which cooperates with the beveled ends to give the outer face of the plate a generally curved form calculated to slide over rather than foul against any part of the car during relative movement of the clevis and such part.

The inner face of the plate 24 at the left end in Fig. 3 is made flat to correspond with the opposed surface of the push rod 16. Adjacent to the opposite end it is provided with a fillet 29 for reenforcing the pin 26. The pin 25 will ordinarily be made to correspond in size with the standard perforations in push rods, cylinder levers, and the like, so that the clevis may be readily substituted for the clevis now in service, and the pin 25 may be received in the holes which ordinarily receive the pin in the conventional clevis. The pin 26 is relatively small as compared to the pin 25 and may be passed through a link of the standard brake chain. At its free end it is provided with a shoulder 30 adapted to bear against the outer face of the plate 21, at 31, the perforation being made sufficiently large to permit it with its shoulder to be passed through in assembling.

The plate 21 is also beveled at its ends, indicated by 32 and 33 and the pins 25 and 26 are rounded or beveled at 34 and 35 to present surfaces that will tend to slide rather than catch, as explained in connection with the other plate 24.

The left end of the plate 21 is enlarged laterally, as shown in Figs. 2 and 4, and on each side of the perforation 22 it is provided with outwardly projecting flanges 36 which are perforated in alignment with the perforation in the pin 25 to receive a cotter key 37. The inner ends of these flanges are beveled at 38.

The intermediate portion of the plate 21 at its outer side is provided with a depression 39 extending from the outer wall of the perforation 23 to a point adjacent to the inner wall of the perforation 22.

The distance between the remote sides of the pins 25 and 26 is approximately equal to the distance between the remote sides of the perforations 22 and 23. In assembling, the 10 pin 26 is passed through the perforation 23 by a movement at a slight angle to the axis of that perforation. This will bring the rounded or beveled end of the pin 25 against the remote wall of the perforation 22 at the 15 inner face of the plate. A blow of a hammer, or the like, will spring the parts sufficient to permit them to take the position shown in Fig. 3 in which the shoulder 30 bearing against the outer face of the plate 21, 20 and the outer wall of the pin 25 bearing against the corresponding wall of the opening 22, hold the parts against displacement. The cotter pin 37 is used as a precaution to insure that the clevis will remain fast even 25 if distorted, or if manufacturing tolerances have so accumulated as to prevent the preferred binding action described.

The outer wall 40 of the perforation 23 is 30 flat and the corresponding wall of the pin 26 is also flat.

In the modified construction shown in Fig. 5, the plates 121 and 122, corresponding to plates 21 and 24, are offset between their ends 35 to dispose the ends 42 and 43 wide enough apart to accommodate the jaw 44 on the push rod 45, which jaw receives the cylinder lever 46. The pin 47 serves to secure both the cylinder lever and the clevis to the jaw 44. Both the plates 121 and 122 are reenforced by sloping ribs 48.

Because this clevis can be applied directly 45 to the small links used in standard brake chains, such chains can be made by merely cutting the proper length from stock and there is no need of the expensive operation of forging a large link on one or both ends. The clevis is of small lateral dimensions only 50 slightly exceeding the dimensions of the chain and is provided with surfaces that tend to slide over rather than engage other parts. The cross-sectional area of each of these plates is such that the plate cannot be inserted through the end link of the chain while the 55 adjacent link is engaged therein. The clevis can be made by casting and at much less cost than the forged clevises now in common use.

I have made use of specific description and 60 illustration in order that the invention might be fully understood, but I do not intend to thereby limit the claims or require them to be interpreted more narrowly than is made necessary by the prior art.

I claim as my invention:

1. A clevis for connecting a small link of a 65 railway brake chain with an end of a brake

operating device, said clevis comprising a plate having an inner surface for fitting against the surface of said device and parallel to the plane of an end link of the chain, a pin carried by said plate and extending at substantially right angles thereto for extending through said device, a second pin also extending at approximately right angles to said plate for extending through said link of the chain, a second plate having perforations to receive said pin, said second plate adapted to lie flat against said device and means on the pins for holding said second plate in parallel relation to said chain link, said plates being provided with reinforcing flanges extending longitudinally thereof.

2. In a brake operating mechanism comprising a chain and an element to which the chain is secured, a clevis comprising a pair of plates, one of which is perforated adjacent to each end, a relatively small comparatively straight pin on the other plate for projecting through a link of the chain and through one of the perforations and having a shoulder beyond said perforated plate, a relatively large comparatively straight pin projecting through the element to which the clevis is to be secured, through the other perforation in the perforated plate and holding the shoulder on the small pin in position to bear on the outer side of the perforated plate permitting the assemblage of the parts although the greatest cross sectional dimension of each of said plates is such that neither plate can be inserted in the end link of said chain while the adjacent link is engaged therein.

3. In a brake operating mechanism comprising a conventional brake chain and an element to which the chain is secured, a clevis for the end link of said chain, said clevis comprising a plate having a comparatively large pin extending outwardly from one end of said plate for engaging said element and a comparatively small pin extending outwardly from the other end of said plate for extending through an end link of said chain, a second plate substantially parallel to said first-named plate and having an opening at each end thereof for receiving the free ends of said pins, said plates being of substantially the same length and each having a cross-sectional area such that the same cannot be inserted through an end link of said chain while the adjacent link is engaged therein.

In testimony whereof I affix my signature.

PERCY B. CAMP.
